RUBBER DOLL HEAD AND METHOD FOR
MAKING THE SAMEMelvin S. Lower, Wadsworth, Ohio, assignor to
The Sun Rubber Company, Barberton, Ohio, a
corporation of Ohio

Application September 30, 1936, Serial No. 103,305

5 Claims. (Cl. 46—167)

This invention relates to eye constructions for hollow rubber dolls and to methods for producing the same.

Heretofore, the usual practise in providing eye constructions for hollow, rubber dolls in which the eyes can close or open depending upon the position of the doll, it has been customary to provide separate sockets in the doll head in back of the eye openings and to provide eye units which are separately received and retained in said sockets, the rubber being molded with a lip about the socket for retaining such eye unit in place. Such a construction is, however, unsatisfactory in that the eyes may become twisted out of place in the sockets and may also be displaced from the sockets into the inside of the head.

The general purpose of the present invention is to provide a rubber doll in which the head is formed with a cavity in back of the usual eye openings so shaped as to receive a unit comprising a pair of opening and closing eye devices which may be of a known type permanently associated together in correct positions from which they cannot be displaced upon flexing the wall of rubber forming the head of the doll and to provide means integral with the doll head for engaging the eye supporting unit and fastening it securely in the head against displacement.

The foregoing and other purposes of the invention are attained in the construction illustrated in the accompanying drawing and described below. It is to be understood that the invention is not limited to the specific form thereof shown and described.

Of the accompanying drawing.

Figure 1 is a vertical section through a hollow rubber doll head and the core on which it is molded and vulcanized.

Figure 2 is an enlarged section through the eye-portion of the doll head.

Figure 3 is a vertical section through the ear portions, looking forwardly, of a doll head embodying the invention, and

Figure 4 is an enlarged section on the line 4—4 of Figure 3.

Referring to the drawing, in carrying out the present invention the core 10 of a known construction upon which the head 11 is formed and vulcanized is provided with portions 10^a, 10^a for forming the eye openings and sockets behind the same and with a bridging portion 12 between the portions 10^a, the portions 10^a and 12 extending into a groove 13 in the core back of the eyes of the doll head in which groove 13 a thick web 14

of rubber is formed for surrounding the eye-sockets. The portions 10^a and 12 accordingly from two eye-sockets 15, 15 with a connecting groove 16 in the web 14.

The present invention contemplates the provision of an eye-unit in which a pair of opening and closing eye structures of a known type shown at 17, 17 are secured to a base or backing plate 18 which may comprise a sheet metal stamping of generally arcuate shape as shown in Figure 4 for supporting the eyes 17 in proper positions in sockets 15 which they are shaped to fit, the backing plate 18 having a reduced shank 18^a fitting in groove 16. The eye devices 17 are secured to the face of the backing plate 18 in any suitable manner as by bending flanges 18^b on the backing plate 18 about the rear portions of the eye structure as best shown in Figure 4.

To secure the eye unit comprising eyes 17 and backing plate 18 in the doll head with the eyes 17 in sockets 15 and the shank 18^a in groove 16, a suitable fastening device such as a rivet 19 may be provided, the head of which may be embedded and vulcanized in the rubber wall of the doll head so that the rivet will project rearwardly out of the web 14 into groove 16. The rivet 19 may be of the pronged type as shown and as illustrated in Figures 1 and 2 may be inserted in a bore 20 in the core in which is a pin 21 having a wedge-shaped end at 21^a for engaging between the prongs of the rivet to position the same for most convenient assembly of the eye unit with the head. As is shown the rivet is positioned so that the prongs may be bent sidewise by a suitable tool extending through the neck opening 11^a in the bottom of the doll head (see Fig. 3).

The shank 18^a of the eye-unit may be provided with a central aperture 18^c to be engaged over the rivet as the eye-unit is assembled in sockets 15 and groove 16 and the prongs of the rivet 19 may be bent in back of the shank as shown in Figures 3 and 4 to secure the eye-unit in place. It will be obvious that other fastening means such as screws, bolts, etc. may be integrally secured in the head of the doll to fasten the eye-unit in place in an equivalent manner.

It will be seen that by the invention a pair of permanently associated eyes may be easily and effectively mounted as a unit in a rubber doll head so as to be properly positioned and permanently retained in place therein both in the manufacture and during the subsequent use of the doll.

Modification of the invention may be resorted to without departing from the spirit thereof or the scope of the appended claims.

What is claimed is:

1. A hollow rubber doll head formed with eye openings and a web of rubber on the inside of the head having eye socket formations back of the eye openings said sockets being connected by a groove extending between the sockets, a fastening device comprising a pronged rivet having a head embedded and vulcanized in the rubber wall of the doll head so as to project rearwardly in said groove and an eye unit having a pair of opening and closing eye devices secured thereto for fitting in said sockets and a shank for fitting in said groove, said shank having an aperture engaged over said projecting rivet, and the prongs of said rivet being bent in back of said shank to secure the eye unit in place in the doll head.
2. A hollow rubber doll head formed with eye openings and eye socket formations back of the eye openings said sockets being connected by a groove extending between the sockets, a fastening device having a head embedded and vulcanized in the rubber wall of the doll head so as to project rearwardly in said groove and an eye unit comprising a base having a pair of opening and closing eye devices secured thereto for fitting in said socket formations and a shank for fitting in said groove, said shank having an aperture engaged over said fastening device and said fastening device having means thereon for securing it to shank to secure the eye unit in place in the doll head.
3. A hollow rubber doll head structure including a rubber wall formed with eye openings and a unit comprising a base having a pair of eyes thereon including socket members for fitting in said openings on the inside of the head, each of said eyes including eye-ball members independently tiltable inside the socket members, and means for securing said unit in said head comprising a fastening device having a portion permanently embedded in the wall of rubber con-

stituting said head and secured to said eye unit.

4. That method for making hollow rubber doll heads with opening and closing eyes which comprises forming a hollow doll head with eye openings with sockets in back of the eye openings securing a portion of a fastening device in the rubber constituting the wall of the doll head between the eye openings by embedding and vulcanizing a portion of a fastening device in said wall whereby the fastening device projects into the head, providing a base, securing eye members in spaced relation on said base, said eye devices having socket members for fitting in said sockets with eye-ball members independently tiltable therein said base providing a connecting shank between the eyes, inserting said unit in the head with the eye devices in said sockets and securing the projecting portion of the fastening device to said shank.

5. That method for making hollow rubber doll heads with opening and closing eyes which comprises forming a hollow doll head with eye openings with sockets in back of the eye openings securing a fastening device in the rubber constituting the wall of the doll head by embedding and vulcanizing a portion of a fastening device in said wall whereby a portion of the fastening device projects into the head, providing a structure including a base securing eye devices for fitting in said sockets in spaced relation on said base whereby to provide a connecting shank, inserting said unit in the head with the eye devices in said sockets and securing the fastening device to said shank, said fastening device comprising a pronged rivet with the prongs extending rearwardly in the groove, said shank being apertured and the rivet being extended through the shank, the prongs of the rivet being bent in back of the shank to retain the unit in place.
